OF ONE-HALF TO ARTHUR W. BEAMAN, OF WORCESTER, MASSA-
CHUSETTS.

VARIABLE-SPEED DRIVING MECHANISM.

No. 807,216.

Specification of Letters Patent.

Patented Dec. 12, 1905.

Original application filed October 24, 1902, Serial No. 128,552. Divided and this application filed December 9, 1903. Serial No. 184,393.

To all whom it may concern:

Be it known that I, RADFORD STOCKBRIDGE, a citizen of the United States, residing at Worcester, in the county of Worcester and 5 Commonwealth of Massachusetts, have invented a new and useful Improvement in Variable-Speed Driving Mechanism, of which the following is a specification accompanied by drawings forming a part of the same and representing 10 my variable-speed mechanism as applied to a shaping-machine, in which—

Figure 1 is a top view of a variable pitman with its actuating mechanism. Fig. 2 represents the variable pitman with its actuating 15 mechanism shown in central vertical sectional view. Fig. 3 is a view of the actuating mechanism for driving the variable pitman, the pitman having been removed. Fig. 4 represents a portion of the mechanism for 20 driving the variable pitman, the crank-plate having been removed to disclose the eccentric; and Fig. 5 represents the mechanism for driving the variable pitman, showing the side opposite that shown in Fig. 3.

25 Similar reference-figures refer to similar parts in the different views.

My invention has for its object to provide an improved mechanism for driving the variable pitman by which a reciprocating movement is given to the ram carrying the cutting-tool; and it consists in the construction and arrangement of parts, as hereinafter described, and set forth in the annexed claims.

This application is a division of my pending 35 application, filed October 24, 1902, Serial No. 128,552.

In the accompanying drawings, 1 denotes the supporting-framework, provided at the top with horizontal ways 2 for a reciprocating 40 ram 3, provided at one end with a head 4, adapted to carry a cutting-tool, these parts being substantially the same as in machines of this class now in common use.

Power is applied to the machine by means 45 of a cone-pulley 5, carried upon a shaft 6, to the inner end of which a pinion 7 is attached, (shown in Fig. 2,) which engages a gear 8, provided with a hub 9, which rotates on the outside of a fixed hub 10, which is provided with 50 a flange 11, by which it is attached to the framework of the machine. Rigidly at-

tached to the inside of the hub 10 is an eccentric 12, having an eccentric-ring 13, which is rotated around the fixed eccentric by means of a sliding block 14, carried by the gear 8 55 and capable of a radial sliding motion in ways 15 on the side of the gear 8 and pivotally connected with the eccentric-ring by a stud 14^a. The eccentric-ring carries a stud 16, upon which is pivotally mounted a sliding block 60 17, capable of a radial sliding movement in a radial slot 18 in a crank-plate 19, provided with a long hub 20, which is journaled inside the fixed hub 10. The crank-plate 19 is also provided with radial ways 21, in which is held 65 a block 22 and radially adjustable therein by means of adjusting-screws 23, which is rotated by the attendant by means of a spindle 24, journaled concentrically with the rotating crank-plate 19 and provided with a 70 squared end 25, Fig. 2, to receive a wrench. The spindle 24 is connected by intermediate gearing 26 with the adjusting-screw 23. The block 22 is provided with a stud 27, on which is pivoted a block 28, capable of sliding in vertical ways 29 29 in a variable pitman 30; pivoted at its lower end 31 upon a stud in the framework of the machine. 75

The upper end 33 of the variable pitman carries a friction-roll 34, which engages a 80 slot 35 in a block 36, carried by the reciprocating ram 3.

The operation of the ram-reciprocating mechanism is as follows: Motion is imparted to the gear 8 by the pinion 7, causing it to 85 rotate around the fixed hub 10. The gear 8 rotates around the fixed eccentric 12 and carries the eccentric-ring 13 by means of the radially-sliding block 14, held in the ways 15 of the gear and pivotally connected with the 90 eccentric-ring by the stud 14^a. As the eccentric-ring is rotated around the fixed eccentric the block 14 will move in and out in the radial ways 15, and thereby impart a variable motion to the eccentric-ring. The 95 rotating eccentric-ring drives the crank-plate 19 through the stud 16 and block 17, held in the radial slot 18 of the crank-plate, and the rotation of the crank-plate 19 imparts a vibrating movement to the pitman 100 30 by means of the block 22, radially adjustable in the ways 21 of the crank-plate,

stud 27, carried by the block 22 and the block 28, pivoted on the stud 27 and held in the vertical ways 29 of the pitman 30. The gear-wheel 8 rotates in the direction of the arrow 5 37, Fig. 1, and the actuating mechanism in Figs. 1 and 2 are shown in the position assumed when the vibrating pitman is in the middle of its forward stroke, which is the cutting stroke of the machine. During the 10 forward stroke of the pitman the crank-block 28 is moving through the upper half of its circular path and farthest from the pivoted end 31 of the pitman, while upon the reverse movement of the pitman or return 15 stroke the crank-block 28 moves through the lower half of its path and nearest the pivoted end 31 of the pitman. Consequently the ram 3 is retarded during its forward stroke and accelerated during its return stroke inde- 20 pendently of the variable movement of the crank-plate. I increase the retardation and acceleration of the pitman, however, by imparting a variable motion to the crank-plate by interposing the eccentric 12 and eccentric- 25 ring 13 between the crank-plate 19 and the driving-gear 8, thereby imparting a variable motion to the eccentric-ring from the driving-gear; from the eccentric-ring to the crank-plate 19. A variable motion has heretofore 30 been imparted to the crank-plate in machines of this class by journaling the crank-plate eccentrically to the axis of its driving-gear and driving the crank-plate by means of a stud carried by the gear and entering a 35 radial slot in the crank-plate. By this method of driving the crank-plate the eccentricity of the crank-plate is limited, and the stud which is carried by the driving-gear is always at the same radial distance from its 40 axis of rotation.

By my improved construction the eccentric is rotated by a stud carried by the eccentric and entering a radial slot in the driving-gear, and when the greatest power is required 45 or during the forward or cutting stroke of the pitman the driving-stud 14^a is nearest the axis of the driving-gear 8, and at the same time the driving power is applied to the gear 8 at its periphery by means of the pinion 7, 50 thereby multiplying the power applied during the cutting stroke of the machine. I am also enabled to materially increase the variation in the movement of the pitman, for the reason that the radial ways 15 can extend 55 from the hub of the gear 8 to its periphery,

thereby allowing a corresponding eccentricity to the fixed eccentric 12.

What I claim as my invention, and desire to secure by Letters Patent, is—

1. The combination with a slotted vibrat- 60 ing pitman and a crank-plate engaging the slot of said pitman, said crank-plate having a radial slot, of a rotating gear journaled concentrically with said crank-plate and having a radial slot and a rotating ring interposed 65 between said gear and said crank-plate and having its axis eccentric to the axis of said gear and said crank-plate, said eccentric-ring engaging the slots in said crank-plate and said gear, whereby the rotation of said gear is imparted to said crank-plate with a vari- 70 able movement.

2. The combination with a framework, of 75 a fixed hollow hub, a crank-plate journaled within said hub, a gear journaled outside said hub and concentrically with said crank-plate, and an eccentric-ring interposed between said gear and said crank-plate, radial slots in said gear and said crank-plate, and sliding blocks engaging said slots and pivot- 80 ally attached to said eccentric-ring.

3. The combination of a rotating gear and 85 a crank-plate journaled concentrically, inter- posed connecting mechanism between said gear and crank-plate whereby the latter is driving at a variable speed from said gear, a slotted vibrating pitman, a sliding block in 90 the slot of the pitman pivotally attached to a block carried by said crank-plate, and means for radially varying the position of said block, comprising a rotating spindle journaled concentrically with said crank-plate.

4. The combination with a framework 95 having a fixed hollow hub, of a rotating gear journaled on the outside of said hub, a crank-plate journaled inside said hub and concentrically with said gear, an eccentric attached to said hub between said gear and crank-plate, a ring turning on said eccentric, means 100 for operatively connecting said gear and said ring, whereby the latter is driven by said gear, and means for operatively connecting said ring and said crank-plate, whereby the latter is driven by said ring.
